UNITED STATES PATENT OFFICE.

EDWIN DE LOE, OF BARTLESVILLE, OKLAHOMA.

BURNER.

No. 913,706.

Specification of Letters Patent.

Patented March 2, 1909.

Application filed July 17, 1907. Serial No. 384,139.

To all whom it may concern:

Be it known that I, EDWIN DE LOE, a citizen of the United States, residing at Bartlesville, in the Cherokee Nation, Oklahoma, 5 have invented certain new and useful Improvements in Burners; and I do hereby declare the following to be a full, clear, and exact description of the invention, such as will enable others skilled in the art to which it app-10 pertains to make and use the same.

This invention relates to new and useful improvements in vapor and gaseous fuel burners and it has particular reference to a burner for use in furnaces and comprising 15 generally a supply pipe formed with a vaporizing coil and provided with burners proper below said coil.

The invention has for its object to provide a burner of novel construction in which the 20 flame shall be always uniform and in which the liability of the burner becoming clogged is reduced to a minimum.

The invention aims as a further object to provide a novel construction, combination 25 and arrangement of parts, the details of which will appear in the course of the following description, in which reference is had to the accompanying drawings, forming a part of this specification, like characters of refer-30 ence designating similar parts, throughout the several views, wherein:

Figure 1 is a sectional view through a furnace illustrating the manner of use of a burner constructed in accordance with the 35 present invention. Fig. 2 is a top plan view of the fuel supply pipe showing the relative arrangement of the coil and the burner. Fig. 3 is an elevation of the burner showing in detail, the curved formation of the flame 40 opening. Fig. 4 is a section on the line 4—4 of Fig. 3.

In the accompanying drawings, the numeral 10 designates a steam boiler furnace provided with a steam dome 11. Within the 45 furnace is a pipe 12 having its body portion formed with a vaporizing coil 13, and rearwardly of said coil being bent recurvately as at 14. The portion 14 lies beneath and in parallelism to the body of the pipe 12 and has 50 connection by means of a T joint 15 with a cross pipe 16. The latter, at its ends, carries elbow joints 17 which are in turn coupled with pipes 18 and the latter carry the burners 19, disposed on each side of the coil 13. 55 The pipe 12, at its outer end has connection

with a jet 20 and the latter is likewise in communication with a pipe 21, leading from the dome 11, the pipe 21 being provided with a controlling valve 22 in order that the supply of steam which is used to induce the feed 60 of oil and combustion may be regulated as desired.

The jet 20 likewise has connection with an oil supply pipe 23 leading from a tank or reservoir 24. The burners 19, at each side of 65 the coil 13, are counterparts in construction. Each of said burners is in the form of a metallic cap having a cylindrical body 25 and an upper closure plate 26 which is preferably integral. At points diametrically opposite of 70 the body 25 curved slits 27 are cut thereinto. These slits extend upwardly in diverging relation to one another so that the flames diverge from each side of the burners, the said slits terminating at opposite points of the 75 junction of the plate 26 with the body 25.

The provision of the slits 27 in the relation stated assures of the two flames from each burner being uniform and constant at all times. These slits are not liable to become 80 clogged or choked and the flames have maximum heat and effect upon the coil 13 with a minimum consumption of fuel. In order that best results can be obtained from the flames, the slits extend upwardly from ap-85 proximately centrally of the height of the burner and converge outwardly to the upper edge of the burner.

The invention is simple in its structural details, inexpensive to manufacture and 90 practical and efficient in use.

From the foregoing description it will be seen that simple and efficient means are provided for accomplishing the objects of the invention but while the elements herein 95 shown and described are well adapted to serve the functions set forth, it is obvious that various minor changes may be made in the proportions, shape and arrangement of the several parts, without departing from the 100 spirit and scope of the invention as defined in the appended claims.

What is claimed is:

1. A heating gas burner consisting of a hollow cylindrical cap having one end closed, 105 said cap being provided with egress slits extending diametrically opposite points of the extreme upper edge of the side wall of the cap, convergently in the direction of the open end of the cap.

2. A heating gas burner consisting of a hollow cylindrical cap having one end closed, said cap being provided with egress slits extending from diametrically opposite points of the extreme upper edge of the side wall of the cap convergently in the direction of the open end of the cap, and the ends of all the slits being in spaced relation to each other and terminating in the same plane a consid-

erable distance removed from the closed end 10 of the cap.

In testimony whereof, I affix my signature, in presence of two witnesses.

EDWIN DE LOE.
